C. SIMPLE

MATRIX ROLLING MACHINE

Filed Nov. 13, 1922

Patented Nov. 6, 1923.

1,473,053

UNITED STATES PATENT OFFICE.

CHARLES SIPLE, OF CHICAGO, ILLINOIS, ASSIGNOR TO THE GOSS PRINTING PRESS COMPANY, OF CHICAGO, ILLINOIS, A CORPORATION OF ILLINOIS.

MATRIX-ROLLING MACHINE.

Application filed November 13, 1922. Serial No. 600,629.

To all whom it may concern:

Be it known that I, CHARLES SIPLE, a citizen of the United States, and a resident of Chicago, in the county of Cook and State 5 of Illinois, have invented certain new and useful Improvements in Matrix-Rolling Machines, of which the following is a specification, reference being had to the accompanying drawing.

10 My invention relates to machines for rolling matrices on chases or forms for the purpose of transferring to the matrix the impression of the type, preliminarily to the use of the matrices in making stereotype plates therefrom. Such machines usually comprise a horizontally disposed reciprocating bed plate which travels between upper and lower cylinders, the lower cylinder serving as an additional support to the bed 15 to prevent deflection thereof, while the upper cylinder bears on the matrix and presses it down into the type bed so as to set therein an impression of the type. The upper cylinder is generally made vertically adjustable so that the pressure applied may be nicely regulated. Such machines are employed in connection with either dry or wet matrices, and it has been found, particularly 20 in connection with the rolling of dry matrices, and especially where the forms have a number of open areas or spaces, that there is a tendency toward wrinkles or creases developing in the matrices during the rolling operation. This, of course, is objectionable 25 because printing plates cast by the use of such wrinkled or creased matrices are apt to be imperfect, and the object of my present invention is to provide an improved machine by which this tendency will be avoided. I 30 accomplish my object as illustrated in the accompanying drawing and as hereinafter described. What I regard as new is set forth in the claims.

In the accompanying drawing, in which I 45 have illustrated only such parts of a matrix rolling machine as will suffice to convey a clear understanding of my invention,—

Fig. 1 is a side elevation;

Fig. 2 is a partial end view;

50 Fig. 3 is a partial perspective view of one of the supports of a tension or matrix-pressing roller hereinafter described; and

Fig. 4 is a partial perspective view of said roller.

55 Referring to the drawing,—5 indicates

the frame of the machine, which is suitably constructed to support a reciprocating plat- 60 en or bed 6 which is arranged to move back and forth on suitable guides, and is pro- pelled in either direction by gears 7 mount- ed on opposite end portions of a transverse shaft 8 and meshing with racks 9 at the under side of the bed 6 near the side margins thereof, as shown in Fig. 2. Between the gears 7 is a lower cylinder 10 also mounted 65 on and rotating with the shaft 8. The sur- face of said cylinder bears against the under surface of the bed 6 and supports it inter- medately as it reciprocates.

Above the bed 6 is an upper cylinder 11 70 corresponding with the cylinder 10 and ar- ranged directly over it on a shaft 12, the axis of which is in the same vertical plane as the axis of the shaft 8, as shown in Fig. 1. Preferably the shaft 12 is mounted in 75 eccentric bushings 13 pivoted in suitable bearings in standards 14 at opposite sides of the machine, so that by adjusting said bush- 80 ings the shaft 12 with the cylinder 11 may be moved vertically to vary the distance be- 85 tween the lower portion of the cylinder 11 and the bed 6. This adjustment may be ac- complished in any suitable way, as by means of pinions 15 carried by a shaft 16 which ex- 90 tends over the cylinder 11, and meshing with seg- mental racks 17 connected with the bush- 95 ings 13. The shaft 16 may be rocked by means of a hand lever 18. Preferably a pin- 100 ion 15, rack 17 and lever 18 are provided at each side of the machine so that the vertical adjustment of the cylinder 11 may be made from either side thereof. These parts are all old and form no part of my present in- 105 vention. The shafts 8 and 12 are geared together by gears 19, 20, as shown in Fig. 2, 110 so that they rotate in unison and their ad- joining surfaces move in the same direction.

In Figs. 1 and 2, 21 indicates a chase or form resting on the bed 6, and 22 indicates a matrix laid upon the form. 23 indicates 100 the usual blanket which overlies the matrix during the rolling operation. From the foregoing description it will be understood that by moving the bed 6 between the cylinders 10, 11 the upper cylinder will roll over 105 the matrix and blanket and will press the matrix down into the interstices of and be- 110 tween the type, so that the lower surface of the matrix will take the impression of the type. In the illustration of Fig. 1 the bed

6 is supposed to move to the right in making such impression. To keep the matrix smooth and flat as it is fed under the cylinder 11 during the rolling operation, I provide a 5 comparatively heavy solid steel roller 24 which is arranged parallel with the cylinder 11 adjacent to the lower portion thereof in such position that it rests upon the upper surface of the matrix as it is carried through 10 the machine, and is caused to rotate by its frictional engagement with the blanket placed thereover. In order that it may operate in this manner the roller 24 is provided at its ends with journals 25 which rest 15 in sockets 26 at the lower ends of arms 27, the upper ends of which are connected with the shaft 16 as shown in Fig. 2. The roller is therefore free to adjust itself vertically so that it rides freely over the upper 20 surface of the blanket, but its weight rests at all times on that portion of the matrix adjacent to the pressure cylinder 11. Consequently as the matrix is fed under said cylinder the roller 24 operates to press down 25 and flatten or iron out any wrinkles or elevated places in that portion of it which is about to be subjected to the pressure of the cylinder 11, and prevents it from being buckled or drawn up by the action of said 30 cylinder. The result is that the matrix does not wrinkle or crease, and a much more nearly perfect impression is obtained than it has been practicable to obtain with the machines heretofore in use. I have not illustrated any source of power for driving the 35 machine, as any suitable means, such as an electric motor, may be employed for that purpose.

So far as I am aware, I am the first in the 40 art to provide a pressing or smoothing device combined with a matrix rolling machine for this purpose, and the claims hereinafter made are to be construed accordingly. Furthermore, I wish it to be understood that 45 my invention, broadly considered, is not

limited to the use of a roller for doing such work, but includes any and all equivalent smoothing means operating to insure proper feeding of the matrix to the pressure cylinder, whether such smoothing means is arranged to rotate or not. 50

What I claim as my invention and desire to secure by Letters Patent, is—

1. A matrix rolling machine comprising a pressure cylinder, means for moving a 55 form and matrix past said cylinder, and means adjacent to said cylinder for exerting a continuous downward pressure upon the matrix in advance of its being acted upon by said pressure cylinder. 60

2. A matrix rolling machine comprising a pressure cylinder, means for moving a form and matrix past said cylinder, and means arranged to continuously bear down 65 on the unpressed surface of the matrix as it moves into position to be acted upon by the pressure cylinder.

3. A matrix rolling machine comprising a pressure cylinder, means for moving a form and matrix past said cylinder, and a 70 roller arranged to roll over the unpressed surface of the matrix as it moves into position to be acted upon by the pressure cylinder.

4. A matrix rolling machine comprising a pressure cylinder, means for moving a form and matrix past said cylinder, and a 75 freely rotatable heavy roller arranged to roll over the unpressed surface of the matrix as it moves into position to be acted on by the pressure cylinder. 80

5. A matrix rolling machine comprising a pressure cylinder, means for moving a form and matrix past said cylinder, and a 85 freely rotatable heavy roller arranged to roll over the unpressed surface of the matrix as it moves into position to be acted on by the pressure cylinder, said roller being free to move vertically.

CHARLES SIPLE.
